Specification of Letters Patent.

Patented June 8, 1920.

Substitute for application Serial No. 727,548, filed October 24, 1912. This application filed October 16, 1918. Serial No. 258,467.

To all whom it may concern:

Be it known that I, JOSEPH BECKER, a citizen of the United States, residing at Washington, in the District of Columbia, have invented a new and useful Improvement in Copying or Enlarging Cameras, of which the following is a specification.

My present patent application, which is identified for convenience of reference in 10 my related applications or patents as Case Bd, is filed in place of my herein merged and now abandoned prior application Case X, Serial No. 727,548, filed October 24, 1912.

My different related applications or 15 patents, specifically referred to above, or hereinafter, may all be listed in their letter name or filing date order, as follows: Case K, filed July 10, 1905, now Patent 1,103,842, issued July 14, 1914; Case O, filed Feb. 9, 1910, 20 now Patent 1,103,343, issued July 14, 1914; Case T, filed August 28, 1911, now Patent 1,142,295, issued June 8, 1915; Case U, filed November 7, 1911, now Patent 1,190,214, issued July 4, 1916; Case X (based on the 25 present Figs. 1 to 5 but now abandoned and merged in the present Case Bd) Serial No. 727,548, filed October 24, 1912; Case Y, Serial No. 732,488, filed November 20, 1912, now merged in and continued as Case Au; 30 Case Au or continuation of Y, filed January 24, 1917, now Patent 1,280,638, issued October 8, 1918.

My present invention consists mainly in a 35 constant velocity ratio mechanism that is specifically adapted for use, as an auxiliary instrument in adjusting and regulating the automatic focusing mechanism disclosed in my said Cases K, O, T, U, X, Y, and Au.

My invention furthermore consists, in 40 incidently, in a novel modified form of the copying or enlarging camera seen in British Patent No. 12734 of 1904 to Cook, which modification was specially devised by me to permit of using my reduction to zero 45 principle in the adjustment and regulation of the said Cook cameras for use with any one of different lenses.

I shall first illustrate my invention as applied to cameras of my said prior Cases K, 50 O, T, and U, which are already provided with all necessary adjusting means, but where the present constant velocity ratio

device may be used to insure that the focusing at a finite distance shall be at a given predetermined scale.

Figure 1 is a plan view of a pantographic linkage of the kind specially adapted for use with the camera shown in Fig. 19 of my said Cases K and O.

Fig. 2 is another form of the same device 30 with adjustments to permit of securing other desirable velocity ratios.

Fig. 3 is a form specially adapted for use in my improved form of the Cook camera.

Fig. 4 is a vertical longitudinal section 65 of my improved Cook camera fully adjusted and regulated for use, its frames and gear being shown in the unity position.

Fig. 5 is a similar view of the same camera 70 in one phase of the process of adjustment.

In its preferred form, Fig. 1, the constant velocity ratio device consists in an articulated parallelogram composed of bars 1, 2, 3, 4 and 5 pivoted as shown at points G, H, 75 K and G', H', K'.

The three parallel bars 2, 5 and 4 are provided with three alined bores A, D, A' of the exact size required to respectively fit the pins A, D, A' of the camera seen in Fig. 80 19 of my said prior Cases K and O.

When this pantographic linkage is mounted on the camera it obliges pins A and A' to move simultaneously, not in the same direction as required in focusing gear, but in 85 opposite directions; and not at a varying velocity ratio as required in focusing gear, but at a constant velocity ratio equal to the ratio of GH to HK or of a to b. Moreover, the same constant proportion holds for the 90 whole distances AD, DA' so that we have

$$\frac{AD}{DA'} = \frac{a}{b} \quad (1)$$

In using this device in any camera some 95 means must first be provided to make due allowance for the extent, sign and location of the internodal space NN' of the lens. This is done in Fig. 19 of my said Cases K and O, by adjusting the longitudinal connections m and m' which involve the internodal distance, and this adjustment is preferably made automatically without knowing the extent, sign or location of the internodal

distance by means of the "infinity and zero method" of adjustment disclosed in said Cases K and O.

Assuming, therefore, that the pintles, A, A' have been properly located on their respective frames by the infinity and zero method, the pantograph of the present Fig. 1 is mounted on the camera with bore A on pin A, bore D on pin D and bore A' on pin A'; and, when so mounted, it obliges the two end frames of the camera to move in opposite directions from the zero position so that the Newtonian space elements PF, F'P' of the lens, henceforth respectively equal to the Newtonian space elements AD, DA' of the gear, shall be in the constant ratio of a to b .

If now the camera frames be moved back and forth until the sharpest available image has been secured, we know that then by Newton's formula

$$PF \cdot F'P' = f^2 \quad \dots \dots \dots (2)$$

By equations 8 and 9 of my said prior Cases K and O, we also have

$$PF = nf = AD \quad \dots \dots \dots (3)$$

$$P'F' = \frac{f}{n} = DA' \quad \dots \dots \dots (4)$$

and, therefore,

$$\frac{PF}{P'F'} = \frac{AD}{DA'} = n^2 \quad \dots \dots \dots$$

or, in view of equation 1 above

$$n^2 = \frac{a}{b} \quad \dots \dots \dots (5)$$

In order to secure any desired copying factor n in the cameras of my Cases K, O, T and U, therefore, all that is necessary is to construct the linkage of Fig. 1 so as to satisfy this last equation, equation 5.

If reduction be desired instead of enlargement, in the same ratio, all that need be done is to turn the device through two right angles about D as axis to set bore A on pin A', and bore A' on pin A.

In Fig. 2 I show a form capable of adjustment to permit of securing any one of three different velocity ratios, to wit, 1 to 1; 9 to 4; and 4 to 1; corresponding, respectively, to copying factors of 1, 1.5, and 2. At H the copying factor n is 1; at H² it is 1.5; and at H³ it is 2. The drawing is to scale and the numbers 26, 40 and 65 indicate relative sizes of the various dimensions.

In this form three separate bores D are needed, so that there shall always be one in proper coöperative alinement with bores A and A'.

The reason why the device as applied to my cameras must have a velocity ratio equal to the square of the desired copying factor is that it acts on the Newtonian space elements of the focusing gear. In cases where

it is used on space elements corresponding to the full conjugate focal distances of the object and image from the nodal points, the velocity ratio should be exactly equal to the copying factor.

This case presents itself in the camera shown, Figs. 7 and 8 of British patent to Cook No. 12,734 of 1904.

In Fig. 3 I show a form of my constant velocity ratio linkage that is specially adapted for use in my improved form of Cook camera, the camera and the linkage being both modified to act in combination while the camera is being adjusted for use with any one of different lenses. This improved Cook camera will hereinafter be referred to for convenience as the Becker-Cook camera.

Becker-Cook camera, (Figs. 4 and 5).

My device is not only useful in Cook, but almost indispensable if the highest attainable efficiency of the lens is to be secured, as will presently appear.

The adjustment of the Cook camera in cases where the focal length of the lens is unknown is an uncertain tentative process made to depend upon the securing of a sharp image of the same size as the original. (See first six lines page 8 of the Cook specification.) Now, in order to secure this equal size image, the operator must perform two mutually interfering operations. In focusing he changes size; and in moving the frames to change size he spoils his focus. Moreover, even when Cook does succeed in securing his desired final result, the same is generally inaccurate because he works from the so-called "optical center" without making allowance for the internodal distance NN'.

For present purposes the Cook camera should be made substantially as in Fig. 4, which shows the parts in what Cook would call the "unity position," because it is the position for copying factor n equal one.

Parts O, L and I, Fig. 4, are, respectively, the object frame, lens frame, and image frame of the camera. The lens frame L is rigidly mounted on a bridge piece 7 which is removably fastened to the rails 10 of the camera bed by screws 8. The upper inside edge of the rails, only one of which appears in the figure, is grooved at 11 to form a slide-way for the carriages 12, 12'. The upper face of carriage 12 is provided with a slide-way 15 for a block 16 on which the object frame O is rigidly fastened. In block 16 is threaded a clamp screw 17 for clamping the block and its object frame O in any desired longitudinal adjustment on carriage 12. The image frame I is similarly mounted in longitudinally adjustable position on carriage 12' by block 16' sliding in groove 15' and held by screw 17'.

A central horizontal cross pin D connecting the guide rails 11 serves as a fulcrum for the quadrant 19 which has perpendicular radial cam slots 20, 20' slidingly engaged 5 with pins A, A' which are rigidly, but adjustably connected with the carriages 12, 12', respectively.

The adjustable connection of pin A with carriage 12 is established by means of an 10 inclined bracket 14, which is fastened to the under side of carriage 12 by screws 13, and which is provided with an inclined adjustment or bracket slot 23 at any desired 15 point of which the pin A may be firmly clamped and held by nut or other suitable clamping means. The bracket 14 is divided by a narrow longitudinal vertical kerf into two similar bracket elements or walls adapted to admit and guide the quadrant 20 19 between them.

The adjustable connection of pin A' with carriage 12' is similarly established by an 25 inclined adjustment or bracket slot 23' formed in the divided bracket 14', which is fixed to its carriage 12' by screws 13' driven into the bottom of carriage 12'.

Bracket 14 has a hole W formed in alignment with the inclined adjustment slot 23, and at the same level as pin D. The 30 diameter of this hole W is made the same as that of pin D so that the hole W may, as explained later, be slid up to snugly admit pin D for holding the carriage 12 in its zero position. Bracket 14' has a similar 35 hole W' in alignment with adjustment slot 23', of the same diameter and at the same level as pin D to permit of holding carriage 12' in its zero position.

The two adjustment or bracket slots 23, 40 23' are disposed in any desired perpendicular relation as shown. The left end of quadrant 19 is perforated to admit a horizontal pin 30 used for temporarily holding the quadrant with its radial cam slots 45 20, 20' in anti-parallel relation to the bracket slots 23, 23', respectively, as shown in the "unity position," Fig. 4. The radial cam slot 20 and the bracket slot 23, being 50 equally but oppositely inclined with reference to the horizontal line W W', are (according to the Merriam International Webster of 1912) "anti-parallel." Radial cam slot 20' and bracket slot 23' are anti-parallel for the same reason; and if the pintles 55 A, A' are supposed removed so as to permit of freely changing the distances WD and DW', this anti-parallel relation of the grooves and slots persists as long as the quadrant 19 is held in its locked position by pin 30, which slides as a bolt through a 60 properly located opening 31, Fig. 5, in rail 10.

Assuming that the exact position of the nodal points, N, N' with relation to the

camera bed 10 has been predetermined, the 35 lens frame L and the quadrant 19 are unmounted and removed to prepare the camera for adjustment.

Carriage 12 is now slid up into its zero position, making WD equal to zero, and it 70 is locked in such position by insertion of pin D; and then having loosened clamp screw 17, the object frame O is moved as required to bring its point P into coincidence with the known position of the nodal point 75 N belonging to the object space. Finally screw 17 is firmly tightened to hold frame O in its thus determined proper adjustment on carriage 12.

Pin D is withdrawn, and carriage 12 is 80 slipped back to the left, and it will be noted that henceforth the varying mechanical space element WD remains equal to the equally varying object distance PN.

Carriage 12' is now moved up into its 85 zero position, making DW' equal to zero, and it is locked in such position by reinserting pin D; and then, having loosened the clamp screw 17', the image frame I is moved as required to bring its point P' into 90 coincidence with the known position of the nodal point N' belonging to the image space. Finally screw 17' is firmly tightened to hold frame I in its thus determined proper adjustment on carriage 12'. 95

Pin D is withdrawn and carriage 12' is slipped back to the right, with its varying distance DW' constantly equal to the 100 equally varying distance N'P' of the image receiving plane P'.

The one-to-one pantograph of Fig. 3 is now mounted, as in Fig. 5, with bore A at W, bore D at D and bore A' at W'.

The lens frame L is then remounted and the frame I is moved into proper position 105 to secure the sharpest image. As DW is surely kept equal to DW' by the pantograph during this focusing operation, the image secured is the equal size image, and we have DW equal to DW' equal to twice 110 the focal length FN of the lens.

Temporary clamps, such as weights, are now applied to carriages 12, 12' to hold the 115 end frames O and I in their thus determined "unity position" and the pantographic linkage is removed. The quadrant 19 is now remounted and locked in the unity or parallel position of Fig. 4 by means of slide bolt 30, and the pintles A, A' are inserted and fixed at the points where the 120 bracket slots 23, 23' are crossed by the radial cam slots 20, 20'. As these cam slots 20, 20' are in their anti-parallel relation to the bracket slots 23, 23', the pins A, A' must now be situated exactly midway between the 125 vertical planes through W, D and W'. If the five points W', A, D, A' and W' all be imagined as projected onto the lens axis

or onto the line $w w'$ parallel to such axis by vertical planes, and if the corresponding lower case letters w, a, d, a', w' be used to name such projections, we shall have, for 5 the unity position of Fig. 4:

$$wa=ad=da'=a'w'=FN=f.$$

In all other positions, and generally, we shall have

$$10 \quad wa=a'w'=f \quad (6)$$

also

$$ad.da'=f^2 \quad (7)$$

15 where ad and da' are the co-varying Newtonian space elements of the focusing gear. Bolt 31 is now withdrawn to free the quadrant 19, and the device is ready for use.

In the structure illustrated I have adhered to Cook's idea of adjusting in the 20 "unity-position" where the ratio $P'N/N'P$, or copying factor n , equals one. This limitation, though convenient, is not essential.

To adjust and regulate my present 25 Becker-Cook camera at any preferred copying factor n , use a pantograph ratio GH/HK and a quadrant ratio da/aw each equal to n .

Thus, to illustrate the application of the 30 rule, suppose n is equal to unity, then the pantograph ratio GH/HK should be 1, as in Fig. 4. For a copying factor n equal 2, these same ratios would be 2, and so on, bore 31 of Fig. 5 being shifted to correspond.

35 NOTE 1.—According to disclosures in my said Case Au my present Becker-Cook camera has a basic angle delta (Δ) that is equal to one right angle.

NOTE 2.—In accordance with other disclosures of my said Case Au, however, the 40 present Becker-Cook camera should preferably be built with a basic angle delta (Δ) that is smaller than a right angle. Changing the basic angle involves no change in 45 principle.

NOTE 3.—The inclined bracket slots 23 and 23', in present Fig. 4, should not be confounded with inclined grooves 215 and 215' in Fig. 3 of my said Case Au, where the 50 present pintles A and A' are identified as V and V'; so that the present Fig. 4, after completion of its adjustments, really corresponds to Fig. 1 of my said Case Au, and not to Fig. 3 of said Case Au, as might easily and incorrectly be assumed.

NOTE 4.—The same said Case Au, in connection with its Fig. 7 and its equation 11, discloses how its special three-point method of adjustment is applicable to the present 60 form of Becker-Cook camera.

NOTE 5.—Instead of plotting the unity positions of the end frames as explained in my said Case Au, the same 3-point method may be used for locating the above referred to $\bar{N}$

and $\bar{N}'$ positions of the end frames, as, by 65 plotting the distance f to the right of Y , and the same distance f to the left of Y' , marks Y and Y' being those seen in Fig. 7 of my said Case Au. Moreover, in some 70 forms of the device it would be easier to adjust and regulate the focusing mechanism proper by making WD and DW' each equal to twice f either with or without the pantograph of Fig. 3, before setting the end frames. All such modifications in procedure 75 may be made without producing any change in the final result.

NOTE 6.—As it is easier to apply temporary clamps to carriages 12 and 12' in the special form of structure that appears in 80 Fig. 4, than it would be to apply such clamps to the end frames O and I of said Fig. 4 as contemplated in my said Case Au, the three point process of adjustment would be facilitated by first adjusting the focusing mechanism proper before paying any attention to the location of the end frames.

NOTE 7.—The present preferred form of 85 my 3-point process of adjustment might then be described as comprising the following 90 steps: (1) calculate f by equation 11 of my said Case Au; (2) mark, on bed 10, the unity position U of frame O, at distance f to the left of Y ; (3) mark, on bed 10, the unity position U' of frame I, at distance f to the 95 right of Y' ; (4) utilizing the WD equal zero position, set and temporarily clamp carriage 12 in position to make WD equal to twice f ; (5) utilizing the DW' equal zero 100 position set and temporarily clamp carriage 12' in the position that makes DW' equal to twice f ; (6) mount the sector 19 on its pivot D, and hold it in the anti-parallel position of Fig. 4 by inserting bolt 30; (7) insert pintle A at the crossing point of cam 105 slot 20 with bracket slot 23, and bolt it to the bracket 14 in its thus determined proper position; (8) insert pintle A' at the crossing point of cam slot 20' with bracket slot 23' and bolt it firmly to bracket 14' in its 110 thus determined proper position; (9) loosen screw 17 and bring frame O into its unity position U , then clamp it firmly to its carriage 12 by tightening screw 17; (10) loosen screw 17' and bring frame I into its unity 115 position U' , and then clamp it firmly to carriage 12' by tightening screw 17'; (11) finally remove the temporary clamps of carriages 12, 12' withdraw bolt 30, and the combination is ready for use.

NOTE 8.—The "zero position" in my present Fig. 4 making distances wd , and dw' equal zero, should not be confounded with the "zero position" of my said Case U making present distances ad , and da' equal to 125 zero.

NOTE 9.—By direct experiment with a very large lens of high grade, I have found

that the calculated Gaussian focal length f of equation eleven, in my said Case Au, may be used to plot, from Y and Y' as origins, a complete focusing scale that is not only accurate for determining focal position, but also remarkably accurate for determining the scale of reproduction or copying factor n .

NOTE 10.—Pintles A and A' of the present Fig. 4, correspond to pintles A and A' of my said Case U, and not to "terminals" A and A' of my said Case Au, where the present pintles A and A' are identified as V and V'.

NOTE 11.—In my said Case Au the present terminals W and W' are found by plotting a distance AW or f , to the left of A; and by plotting an equal distance A'W' or f to the right of A'.

NOTE 12.—The terminals A, A' of my said Case Au are found in the present Fig. 4 by plotting a distance WA or f , to the right of W; and by plotting an equal distance W'A' or f , to the left of W'.

NOTE 13.—The Case Au end frame terminals A, A' may, therefore, be located on line WW' of the present Fig. 4 by simply producing the verticals aA and a'A' until they meet with the horizontal WW'.

What I claim as my invention and desire to secure by Letters Patent is:

1. The combination with a photographic camera comprising a lens support, an image support and an object support, and ways adapted to guide two of said supports with relation to the third; of mechanism for connecting the said three supports to compel the image and object supports to move simultaneously in opposite directions with re-

lation to the lens support at a constant velocity ratio.

2. The combination with a photographic camera comprising a lens support, an image support and an object support, and ways adapted to guide two of said supports with relation to the third; of mechanism for connecting the said three supports to compel the image and object supports to move simultaneously in opposite directions with relation to the lens support at a constant velocity ratio equal to unity.

3. The combination with a photographic camera comprising a lens support, an image support and an object support, and ways adapted to guide two of said supports with relation to the third; of mechanism for connecting the said three supports to compel the image and object supports to move simultaneously in opposite directions with relation to the lens support at a constant velocity ratio, such mechanism consisting in a linkage pantograph.

4. The combination with a copying or enlarging camera having focusing gear of the type adapted to determine structural co-varying space elements such as WD and DW' respectively equal to the full conjugate focal distances PN, N'P' of the lens; such gear being so constructed as to permit of reducing either of its said mechanical space elements WD and D'W' to zero value.

In testimony whereof, I have signed my name to this specification.

JOSEPH BECKER.

In the presence of—

EDNA H. RAY.
